1

Latin name of the genus and species: The Latin name of the genus and species of the novel variety disclosed herein is *Callistemon* R. Br.

Variety denomination: The inventive variety of *Callistemon* disclosed herein has been given the variety denomination 'CNU07'.
5

BACKGROUND OF THE INVENTION

Parentage: 'CNU07' is the result of a controlled cross-pollination breeding program carried out by the inventor at a commercial plant breeding facility in Cobbitty, New South Wales, Australia in October of 2014. The inventor performed a controlled cross-pollination of the seed parent, *Callistemon* 'Hot Pink' (South African Plant Breeder's Rights grant number ZA 20043189) with *Callistemon* 'Mauve Mist' (unpatented), the pollen parent. The resulting seedlings were grown for two years to evaluate for new and distinct characteristics. In October of 2016, the inventor selected the new *Callistemon* plant for its compact growth habit and white flowers. This new and distinctive cultivar was given the name 'CNU07'.
10

Asexual Reproduction: Asexual reproduction of 'CNU07', by way of stem cuttings, was first initiated in 2016 in Cobbitty, New South Wales, Australia. Through greater than four subsequent generations, the unique features of this cultivar have proven to be stable and true to type.
20

SUMMARY OF THE INVENTION

The cultivar 'CNU07' has not been observed under all possible environmental conditions and the phenotype may

(57) **ABSTRACT**

A new and distinct variety of *Callistemon* plant named 'CNU07' which is characterized by the combination of a compact and rotund growth habit, oblong inflorescence comprised of an abundance of white flowers, and the stability of all characteristics from generation to generation.

2 Drawing Sheets

2

vary somewhat with variations in environment such as temperature, day length, and light intensity, without, however, any variance in genotype. The following traits have been repeatedly observed and are determined to be the unique characteristics of 'CNU07'. These characteristics in combination distinguish 'CNU07' as a new and distinct *Callistemon* cultivar:

1. *Callistemon* 'CNU07' exhibits a compact growth habit; and
2. *Callistemon* 'CNU07' exhibits oblong, cylindrical inflorescence with an abundance of white flowers; and
3. *Callistemon* 'CNU07' exhibits flowers with white exserted stamens.

BRIEF DESCRIPTION OF THE FIGURES

FIG. 1 illustrates, as nearly true as it is reasonably possible to make the same in color photographs of this type, an exemplary plant of 'CNU07'. This plant is approximately 36 months old.

FIG. 2 illustrates, as nearly true as it is reasonably possible to make the same in color photographs of this type, the typical inflorescence of 'CNU07'.

BOTANICAL DESCRIPTION OF THE PLANT

The following observations and measurements were made in May of 2022 and describe a 6-year-old 'CNU07' plant grown in the ground in Clarendon, New South Wales, Australia. The plant was allowed to grow with full sun

exposure and maintained with sporadic overhead irrigation during prolonged drought conditions and slow-release granular fertilizer applications. The plant received a light prune, biannually. No pest or disease control measures were utilized in production.

Those skilled in the art will appreciate that certain characteristics will vary with older or, conversely, with younger plants. 'CNU07' has not been observed under all possible environmental conditions. Where dimensions, sizes, colors and other characteristics are given, it is to be understood that such characteristics are approximations or averages set forth as accurately as practicable. The phenotype of the variety may differ from the descriptions set forth herein with variations in environmental, climactic and cultural conditions. Color notations are based on *The Royal Horticultural Society Colour Chart*, The Royal Horticultural Society, London, 1986 (third edition).

A botanical description of 'CNU07', comparisons with the parents and a comparison with the most similar variety of common knowledge are provided below.

General plant description:

Growth habit.—Evergreen shrub with a compact, globular growth habit.

Plant profile.—Rotund.

Height.—110 cm from the soil level to the top of the foliar plane.

Plant spread.—90 cm.

Growth rate.—Moderately fast.

Plant vigor.—Moderately vigorous.

Propagation type.—Stem cuttings.

Time to produce a rooted cutting.—Approximately 120 days to produce a rooted cutting at approximately 25 degrees Celsius.

Time to produce a finished plant.—32 weeks to produce a fully rotted 15 cm container.

Disease resistance.—Neither resistance nor susceptibility to typical *Callistemon* pests and diseases has been observed.

Environmental tolerances.—Adapt to, at least, USDA Zones 9 through 11; moderate tolerance to rain; moderate to high tolerance to wind; drought tolerant once established.

Root system:

General.—Moderately dense and freely branched root ing; roots are moderately fibrous.

Distribution in the soil profile.—Shallow to moderately deep.

Stem:

General branching habit.—A single main stem, freely branching from the base, with an abundance of lateral branches.

Quantity of main stems per plant.—1.

Diameter of the main stem.—14.0 cm at soil level.

Abundance of lateral branches.—Abundant.

Length of lateral branches.—Approximately 83 cm.

Diameter of lateral branches.—Approximately 1.0 cm.

Internode length.—Approximately 0.4 cm.

Attitude of lateral branches.—Outward to upright.

Aspect.—Rounded.

Texture, juvenile.—Tomentose.

Texture, mature and oldest wood.—Glabrous and becoming progressively fissured and furrowed with age, followed by exfoliation of the outer bark in small segments, revealing yet more fissured and furrowed bark beneath.

Luster.—Slightly glossy to matte.

Strength.—Strong.

Color, juvenile lateral branches.—Yellow-green, nearest RHS 151B, and moderately suffused with greyed-red, RHS 181B.

Color, mature lateral branches.—Greyed-orange; nearest to in between 165B and 165C.

Color, main stem.—Exfoliating bark is a combination of greyed-green and brown, nearest to RHS 196A, 200A, 200B, and 200D; exposed wood below the exfoliating bark is greyed-orange, nearest to a combination of RHD 164A, 164B, and 164C.

Foliage:

Arrangement.—Whorled.

Division.—Simple.

Attachment.—Petiolate.

Attitude.—Upward and outward.

Lamina.—Shape — Nearest to oblanceolate. Aspect — Flat. Dimensions — 7.2 cm long and 1.2 cm wide. Apex — Broad acute with a very short, soft mucronate tip. Base — Cuneate. Margin — Entire; not undulated. Texture of the juvenile foliage, adaxial surface — Tomentose. Texture of the juvenile foliage, abaxial surface — Tomentose. Texture of the mature foliage, adaxial surface — Coriaceous; glabrous. Texture of the mature foliage, abaxial surface — Coriaceous; glabrous. Luster of the juvenile foliage, adaxial surface — Matte. Luster of the juvenile foliage, abaxial surface — Matte. Texture of the mature foliage, abaxial surface — Matte to slightly glossy. Texture of the mature foliage, abaxial surface — Matte. Color — Juvenile foliage, adaxial surface — Yellow-green, nearest to in between RHS 151B and 151C, and lightly to moderately suffused with greyed-red, RHS 181B. Suffusion diminishes with age. Juvenile foliage, abaxial surface — Yellow-green, nearest to RHS 151C, and moderately to heavily suffused with greyed-red, RHS 181B. Suffusion diminishes with age. Mature foliage, adaxial surface — Green, nearest to RHS 139B. Mature foliage, abaxial surface — Green, nearest to RHS 139C. Venation — Pattern — Pinnate. Color, adaxial surface — Same as the surrounding foliage; green, nearest to RHS 139B. Color, adaxial surface — Same as the surrounding foliage; yellow-green, nearest to RHS 139C.

Petiole.—Length — 0.20 cm. Diameter — 0.15 cm at the base. Strength — Strong. Texture, juvenile — Tomentose. Texture, mature — Smooth; glabrous. Luster — Matte. Color, adaxial and abaxial surfaces — Juvenile petioles are colored red-purple, nearest to RHS 186A. Mature petioles are yellow-green, nearest to RHS 152C.

Stipules.—None observed.

Inflorescence:

Habit.—Terminal leafy spikes, borne directly on the lateral branches.

Natural flowering season.—Heaviest bloom period is spring, with sporadic flowering through summer and a second larger flush of blooms in autumn, in Zone 9 of the United States.

Time to flower or response time.—Approximately 6 months.

Dimensions.—Largest inflorescence observed is 4.8 cm long and 4.6 cm in diameter.

Quantity of flowers per inflorescence.—21 to 27 flowers, as observed.

Peduncles.—None.

Flower buds:

Shape.—Broad oblong to obovoid.

Length.—7.0 mm.

Diameter.—3.5 mm.

Texture.—Coriaceous; proximal end at the calyx tube is tomentose and distal end at the flower petals is glabrous.

10

Luster.—Slightly glossy.

Color.—Yellow-green, nearest to in between RHS 144A and 144B; immature sepal lobes are suffused with green-white, nearest to RHS 157D.

15

Flower:

Shape, type.—Rotate, with a single whorl of petals.

Attachment.—Sessile.

Flowering habit.—Freely flowering.

Attitude.—Upright to outward.

Flower longevity on plant.—Approximately 7 to 10 days.

20

Persistent or self-cleaning.—Self-cleaning.

Fragrance.—Non-fragrant.

Diameter.—Diameter of the corolla is 12.5 mm, excluding the exerted stamens.

25

Depth.—Depth of the corolla is 6.5 mm, excluding the exerted stamens; the depth including the stamens is 26.0 mm.

Pedicels.—None; flowers are sessile.

Calyx.—Shape — Campanulate with sepal lobes adpressed to the corolla at anthesis. Length — 5.7 mm, including the sepal lobes. Diameter — 3.5 mm, distally, at the sepal lobes. Color of the calyx tube — Yellow-green, nearest to a mixture of RHS 144C and 145A. Sepal lobes — Quantity — 5. Shape — Deltoid. Dimensions — 1.0 mm long and 2.0 mm wide at the base. Apex — Obtuse. Base — Fused to the calyx tube. Margin — Entire. Texture — Tomentose. Luster — Matte. Color — Yellow-green, nearest to a mixture of RHS 144C and 145A.

30

Petals.—Quantity — 5. Arrangement — Rotate. Length — 3.0 mm. Width — 2.4 mm. Shape — Near orbicular. Apex — Obtuse. Base — Truncate. Margin — Entire; light undulation. Texture, inner surface — Glabrous; coriaceous. Texture, outer surface — Glabrous; coriaceous. Petal color — When opening, inner surface — Yellow-green, nearest to RHS 150D. When opening, outer surface — Yellow-green, nearest to RHS 151D. Fully opened, inner surface — Yellow-green, nearest to RHS 150D. Fully opened, lower surface — Yellow-green, nearest to RHS 151D. Petal venation color — No venation is visible.

35

Reproductive organs:

Androecium.—Stamens — Quantity — Ranging from 38 to 44, as observed. Anthers — Attachment — Dorsifixed. Shape — Oblong. Dimensions — 1.0 mm long and 0.5 mm wide. Color — Yellow-white, RHS 158A, and aging to greyed-orange, nearest to in between RHS 165B and 166C. Filaments —

40

Length — 20.0 mm. Diameter — 0.3 mm. Color — White, nearest to RHS 155A. Amount of Pollen — Moderately abundant. Pollen color — Yellow, nearest to RHS 1B.

Gynoecium.—Pistil — Quantity — One. Length — 19.0 mm. Style — Length — 18.25 mm, on average. Diameter — 3.0 mm at the ovary. Color — Yellow-green, RHS 145D, at the ovary and becoming progressively darker towards the stigma; color just below the stigma is nearest to RHS 144C. Stigma — Shape — Near globular. Length — 0.75 mm. Diameter — 0.5 cm. Color — Yellow-green, RHS 144C, and lightly suffused with yellow-green, RHS 151D. Ovary position — Inferior.

Seed and fruit: Seeds not observed.

COMPARISONS WITH THE PARENT PLANTS

Plants of the new cultivar 'CNU07' differ from its seed parent, *Callistemon* 'Hot Pink' (South African Plant Breeder's Rights grant number ZA 20043189), by the characteristics described in Table 1.

TABLE 1

Characteristic	'CNU07'	'Hot Pink'
General coloration of the stamens.	White.	Red-purple.

Plants of the new cultivar 'CNU07' may be distinguished from its pollen parent, *Callistemon* 'Mauve Mist' (not patented), by the characteristics described in Table 2.

TABLE 2

Characteristic	'CNU07'	'Mauve Mist'
General coloration of the stamens.	White.	Purple.

COMPARISON WITH THE MOST SIMILAR VARIETY OF COMMON KNOWLEDGE

Plants of the new cultivar 'CNU07' may be distinguished from the most similar known comparator, *Callistemon* 'CNU01' (co-pending U.S. patent application Ser. No. 17/803,225), by the characteristics described in Table 3.

TABLE 3

Characteristic	'CNU07'	'CNU01'
Growth habit.	Upright.	Spreading.
Plant height.	Shorter than 'CNU01'.	Taller than 'CNU01'
Plant width.	Broader than 'CNU01'.	Narrower than 'CNU01'.
Inflorescence size.	Smaller than 'CNU01'.	Larger than 'CNU01'

That which is claimed is:

1. A new and distinct variety of *Callistemon* plant named 'CNU07', substantially as described and illustrated herein.
